UNITED STATES PATENT OFFICE.

JOSEPH P. RUTH, JR., OF DENVER, COLORADO.

FLOTATION APPARATUS.

Application filed August 16, 1917. Serial No. 186,602.

To all whom it may concern:

Be it known that I, JOSEPH P. RUTH, Jr., a citizen of the United States, residing at the city and county of Denver and State of Colorado, have invented certain new and useful Improvements in Flotation Apparatus; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in flotation apparatus, my object being to provide a construction of this class which shall efficiently perform the function of separating the metallic values from the pulp by causing said values to rise to the top of the pulp through the medium of oil and air mingled with the pulp, whereby an emulsification of such elements is produced.

The apparatus consists of a series of connected units, one of which is preferably an emulsifier, whose only function is the thorough mixing of the pulp, the oil and air, as the material to be treated is fed to the apparatus. The other units of the machine, 20 each consists of an agitating compartment and a separating compartment, each agitating compartment being provided with a cut-off baffle vertically disposed on the side toward the adjacent agitating compartment, 25 whereby a definite amount of pulp is separated from that in the first agitating compartment and overflows into the adjacent agitating compartment, while the overflow of the froth upon the first agitating compartment, passes into its companion spitzkasten or separating compartment, from 30 which it finally passes to a launder. By virtue of this construction, the pulp which passes to the second agitating compartment, 35 is separated from the body of the pulp in the first agitating compartment, at a point somewhat below the surface of the pulp, thus limiting the possible discharge of froth with the flow of pulp into the second agitating compartment, and at the same time maintaining a predetermined level of the pulp in 40 all the units of the machine except the emulsifying unit in which the spitzkasten into which the pulp to be treated is originally fed, is preferably kept empty through the

50 medium of the centrifugal pump employed in the agitating compartment of the emulsifying unit, this pump having a relatively large capacity as compared with the feed of the pulp into the companion spitzkasten.

Further features of the invention reside in maintaining the same level in both agitating and separating compartments, the partition not extending to this level, in providing a free space above this level for the 65 free movement of froth, and in the separate introduction of gas and liquid, whereby the gas is finely divided and separated by definite quantities of the upwardly moving liquid and the diffusion of the gas is maintained. By maintaining the level in both compartments the same with the partition terminating below the level and no froth obstruction above the level, the froth flows off freely and is not broken up and carried 70 below the surface as is the case where the overflow falls to a lower level.

Having briefly outlined my improvement I will proceed to describe the same in detail, reference being made to the accompanying drawing, in which is illustrated an embodiment thereof. In this drawing:

Fig. 1 is a top plan view of my improved apparatus.

Fig. 2 is a longitudinal section taken on the line 2—2, Fig. 1.

Fig. 3 is a cross section taken on the line 3—3, Fig. 1.

Fig. 4 is a perspective view partly broken away.

Fig. 5 is a similar view shown on a larger scale and with the agitating member slightly raised from its normal position.

Fig. 6 is a top plan view of a member located in the bottom of each agitating compartment.

Fig. 7 is a similar view of a cooperating member.

Fig. 8 is a perspective view of the apparatus in which one of the units is employed for emulsifying purposes only.

Fig. 9 is a cross section taken through the emulsifying unit of the apparatus.

Fig. 10 is a detail view illustrating means for regulating the supply of air to the agitating compartments of the various units, the parts being shown on a larger scale.

Fig. 11 is a top plan view partly in section of a part of the construction shown in Fig. 10.

Fig. 12 is a vertical longitudinal section of the adjustable plug shown in Fig. 10.

Fig. 13 is a top plan view of the agitator head employed in the agitating compartments of my apparatus, the hollow shaft connected therewith being shown in cross section.

Fig. 14 is a section taken on the line 14—14, Fig. 13.

10 The same reference characters indicate the same parts in all the views.

Let the numeral 5 designate a tank containing a number of units 6, each unit consisting of an agitating compartment 7 and 15 a spitzkasten or separating compartment 8. In Fig. 8 where I have shown the apparatus provided with an agitating compartment 9 and a feeding compartment 10, each unit of the apparatus including the emulsifying

20 unit has a cavity at the bottom of the agitating compartment, which cavity is formed by the cutaway part 12 of the member 13 (see Fig. 7). This part 13 is placed underneath a bottom member 14 and in close contact therewith, the member 14 having an opening 15 which is in communication with the recess or chamber 12 of the member 13.

In other words, the parts 13 and 14 are two boards, part 13 being underneath the part 30 14 and the cavity or chamber 12 has a depth equal to the thickness of the board 13 and the inner portion 16 of this cavity registers with the opening 15 of the board member 14. The cavity 12 is in communication, as shown

35 at 17, with the bottom of the separating compartment of the unit, so that the material under treatment may be pumped from the separating compartment into the agitating compartment, and this pumping function is accomplished through the medium of a rotary head 18, whose lower extremity is provided with a hollow part 19 which communicates with a number of passages 20 formed in the head and whose outer extremities are at the periphery thereof. The head 18 is secured to the lower extremity of a hollow shaft 21, whose upper extremity is in communication with the atmosphere and whose lower extremity is in communication

45 with the inner extremities of a number of passages 22 of the head whose outer extremities are in communication with hoods 23 which are offset from the body of the head, whereby partial vacuums are formed during 50 the rotation of the head in the direction indicated by the arrows in Fig. 13. At the same time the rotation of the head by virtue of the centrifugal force developed draws the pulp under treatment from the cavity 12

55 and the separating compartment of the unit, into the agitating compartment, and this is true as before stated, of the emulsifying unit, and of all the other units of the apparatus.

60 65 The object of the emulsifying unit 4 is to

thoroughly mingle the air, oil and pulp in order that the flotation function may be properly carried out. The material to be treated is first fed into the compartment 10 of the emulsifying unit and passes therefrom into the cavity 12 of the agitating compartment 9 of this unit. It is intended when the apparatus is in use to maintain the compartment 10 of the emulsifying unit substantially empty, whereby a relatively large 75 quantity of air may be drawn into the pulp with the material as it passes from the compartment 10 into the compartment 9. In this case air may also be drawn into the pulp in the agitating compartment through the 80 medium of the hollow shaft 21 and the air passages 22, or not as may be desired. In other words, it is not necessary to rely upon the air introduced through the medium of the hollow shaft 21, since by so operating the 85 head of the agitating compartment of the emulsifying unit that its pumping capacity is greater than the volume of pulp fed into the compartment 10, any desired quantity of air may be introduced into the pulp by way 90 of the compartment 10. The hollow shaft 21 of the emulsifying unit is rotated at a much higher speed than the corresponding shafts on the separating units. This is indicated in Fig. 8, in which the pulley 24 95 through the medium of which power is transmitted to the hollow shaft 21 of the emulsifying unit, is considerably smaller than the pulleys 25 attached to the hollow shafts of the other units. The two compartments 9 100 and 10 of the emulsifying unit are separated above the bottom opening 17, by a partition 26; while the two compartments 9 and 10 of the emulsifying unit are separated from the corresponding compartments 7 and 8 of the 105 adjacent separating unit by a partition 27 which is provided with a recess 28 at the top and in communication with the upper portion of the compartment 9. One extremity of short trough 29 is connected with 110 the recess 28 while its opposite extremity is arranged to discharge into the separating compartment 8 of the adjacent separating unit.

The compartments 7 and 8 of each unit 6 115 are separated by a partition 30 and there is an overflow from the compartment 7 of each unit into the compartment 8 of the same unit, while the mineralized froth overflows at the top of the inclined wall 31 of each 120 unit 6 into a launder 32 or 33 as may be desired. A bridge plate 34 is hinged at 35 between the two launders. When this plate is in the position shown in Fig. 9, the material from the separating compartment of 125 the unit passes into the launder 32. If, however, it is desired that the froth from any unit shall pass into the launder 33, the plate 34 is adjusted to close the launder 32 at the top, in which event the material flows over 130

the plate which bridges the space between the launder 33 and the unit, allowing the material to enter the launder 33, in which event it is returned to the corresponding 5 separating compartment through the medium of a conduit 36. In other words, if the mineralized froth from any unit is not sufficiently free from gangue, the plate 34 is adjusted to cause it to enter the launder 10 33, which as well as the launder 32 is common to all of the units, there being a separate plate 34 for each unit, as best illustrated in Fig. 8. In order that a part of the material from the agitating compartment of 15 each unit 6 may enter the corresponding compartment of an adjacent unit 6, a baffle member 37 is spaced from a partition 38 separating the agitating compartments, said baffle being supported by the side walls of 20 the agitating compartment and extending both above and below the top of the partition 38. The upper edge of the baffle member 37 extends above the top of the partition 38, while the lower edge of this member extends below the upper edge of said partition. 25 Hence, the portion of the pulp which passes from the agitating compartment 7 of one unit into the corresponding compartment 7 of an adjacent unit, is separated from the 30 body of the pulp below the surface of the latter. The passage of the pulp from one agitating compartment 7 to another through the medium of the corresponding baffle member 37, is illustrated by arrows in Fig. 2. 35 It should be explained that the upper edge of the baffle 37 is of the same height as the corresponding edge of a partition 68 which separates the compartments 8 of any two adjacent separating units, while the upper 40 edge of the partition 38 of each unit, is at the same level as the corresponding edge of a partition 30 separating the compartments 7 and 8 of each unit 6.

Hence, when the machine is in operation 45 the mineralized froth is continually passing from the agitating compartment 7 over the upper edges of the partitions 30 into the adjacent compartments 8, while a portion of the pulp from each agitating compartment 50 7 is passing over the upper edge of the partition 38 into the adjacent agitating compartment of another unit by virtue of the employment of the baffle 37. Attention is called to the fact that the pulp between the 55 baffle 37 and the partition 38, is prevented from entering the adjacent separating compartment or spitzkasten 8 by a closure member 41 which extends above the upper edge 40 of the partition 30, its upper extremity 60 lying in the same plane as the upper edges of the adjacent baffle and the partition 38.

Provision is made for regulating the supply of air to the pulp through the hollow shafts 21, and one form of construction 65 which I may employ for this purpose is

illustrated in detail in Figs. 10, 11 and 12. The device employed consists of a hollow plug 42 adapted to enter the upper extremity of each hollow shaft, and in order that the adjustment of this plug may be effected 70 while the shaft is in operation, I provide a lever 43 which is fulcrumed, as shown at 44, on an oscillatory arm 45 pivoted on a stationary support, as shown at 46. The plug 42 has upper and lower members 47 and 48 75 grooved to receive bearing balls 49, while a ring 50 is grooved on its upper and lower faces to receive the said balls, this ring surrounding the plug and being trunnioned as shown at 51 in grooves 52 formed in the opposite side parts 53 of a bifurcated part 54 of the lever, this bifurcated part being located between the manipulating arm 55 and the part 56 adjacent the fulcrum 44. The plug 42 as illustrated in the drawing, has 80 a V-shaped opening 57 formed in two opposite sides, the opening being largest at the bottom and tapering upwardly. Hence, it will be understood that as the plug is moved downwardly into any hollow shaft 21, the 85 entrance of air to the shaft will be diminished and finally may be entirely cut off, by a proper construction and arrangement of the plug-supporting mechanism.

From the foregoing description the use 90 and operation of my improved flotation process will be readily understood. While the apparatus may be successfully operated without the employment of a special emulsifying unit, I prefer to employ the latter, 100 since by virtue of such employment a special initial emulsification of the material may be effected and this may be very important in carrying out the flotation process and particularly so in the case of some ores. 105

In the form of construction shown in Figs. 1 and 2 the emulsifying unit is not disclosed though such a unit may be placed at the left hand extremity of this construction in which event the apparatus would be substantially 110 the same as illustrated in Fig. 8.

Assuming that the construction employed is that disclosed in the last named figure, the operation will be as follows:

The material to be treated is first discharged through the medium of a spout or conduit 58 into the compartment 10 of the emulsifying unit 4 and by virtue of the rapid rotation of the agitating head within the adjacent agitating compartment 9 the 115 material is drawn through the medium of the centrifugal force developed in the said head, from the bottom of the compartment 10, through the opening 17 into the shallow chamber 12 in the bottom of the agitating 120 compartment 10 and thence through the short hollow member 19 of the head 18, whence it flows through the passages 20 in the said head and escapes therefrom at the outer extremities of the latter to the agitat- 125 130

ing compartment and rises therein filling the said compartment. It is the intention to so regulate the speed of the agitating head of this unit as to maintain the adjacent spitzkasten 10 substantially empty whereby a relatively large quantity of air will be delivered to the pulp in this unit. At the same time additional air if desired may be introduced through the medium of the hollow shaft 21 or this shaft may be closed at the top by the proper adjustment of the plug 42. By the rapid movement of the agitating head of this unit, together with the arrangement for the introduction of a relatively large quantity of air, a thorough emulsification of the pulp, air and oil will be effected, and as this emulsified product rises in the compartment 9, it will flow into the compartment 8 of the adjacent separating unit through the medium of the short conduit or trough 29 heretofore described. It is then that the process of separating the mineral from the pulp in reality begins; and the pulp passes from the compartment 8 of the first unit 6 into the agitating compartment 7 of the same unit, and rises therein, the pulp overflowing from the agitating compartment 7 into the compartment 8 and the froth passing thence from the last named compartment into one of the launders 32 or 33 depending on the adjustment of the hinged plate 34. If for any reason the mineralized froth is not sufficiently free from gangue or impurities, plate 34 is adjusted to close the launder 32 and allow the material to pass into the launder 33 and thence into the conduit 36 and back into the bottom of the separating compartment whence it will again pass into the agitating compartment for retreatment, while if this froth is sufficiently clean or free from gangue, it will enter the launder 32 in the first instance and pass to a suitable receptacle for the mineralized froth or concentrates. As soon as the pulp fills the agitating compartment 7 of any unit 6 a portion of it passes into the adjacent agitating compartment of the next unit, this portion passing between the baffle 37 and the partition 38 and finally overflowing over the last named partition into the adjacent agitating compartment. In this way the agitating compartments of all of the units 6 are kept full when the apparatus is in use and has been operating a sufficient length of time to completely fill or charge the entire apparatus. It will thus be noted that the material within the units 6 automatically and by gravity assumes a predetermined level whereby both compartments of each unit of the entire apparatus are kept full, the pulp continually flowing over the upper edge 40 of the partition 30 from one agitating compartment 7 into the adjacent separating compartment 8, while a portion of

the pulp is continually flowing over the upper edge of each partition 38 from the agitating compartment of one unit into the adjacent agitating compartment of another unit. In the last unit 6 of the apparatus or that farthest to the right in Figs. 1, 2 and 8, the compartment 7 corresponds in position and function with the agitating compartment 7 of the other units except that in this last compartment 7 there is no agitator. The lighter gangue is drawn off from the last compartment 7 at the top while the heavier gangue settles in the bottom and is drawn off through a conduit 62. Furthermore, the overflow from the last compartment 7 to the corresponding compartment 8 results in the further settling of gangue in the last compartment 8 and this gangue is drawn off through a conduit 63. The concentrate or mineralized froth which enters the launder 32 may be drawn off through a pipe or conduit 64.

Having thus described my invention, what I claim is:

1. In flotation apparatus, a plurality of units each comprising an agitating compartment and a separating compartment, the agitating compartment of one unit having an overflow into the separating compartment of its own unit, and an overflow into the contiguous agitating compartment of the adjacent unit independent of the overflow into said separating compartment.

2. In flotation apparatus, the combination of a plurality of units each comprising an agitating compartment and a separating compartment, the agitating compartment of one unit having an overflow into the separating compartment of its own unit and an overflow into the contiguous agitating compartment of the adjacent unit, the separating and agitating compartments of each unit being in communication at the bottom, and means for circulating the pulp.

3. In flotation apparatus, the combination of a plurality of units each comprising an agitating compartment and a separating compartment, the agitating compartment of one unit having an overflow into the separating compartment of its own unit and an overflow into the contiguous agitating compartment of the adjacent unit, the separating and agitating compartments of each unit being in communication at the bottom, and means located within the agitating compartment of any unit for circulating the pulp from the separating compartment into the agitating compartment.

4. In flotation apparatus, the combination of a plurality of units each comprising an agitating compartment and a separating compartment, the agitating compartment of one unit having a free overflow from the top into the separating compartment of its own unit, and a restricted overflow into the con-

tiguous agitating compartment of the adjacent unit independent of the overflow into said separating compartment.

5. In flotation apparatus, the combination 5 of a plurality of units each comprising an agitating compartment and a separating compartment, means for causing a free overflow from the top of the agitating compartment of one unit into the separating compartment of its own unit, and means, for 10 causing a restricted overflow from the agitating compartment of one unit into the contiguous agitating compartment of the adjacent unit independent of the overflow into 15 said separating compartment.

6. In flotation apparatus the combination 20 of a plurality of units each comprising an agitating compartment and a separating compartment, means for causing the pulp to overflow from the agitating compartment of one unit into the separating compartment of the same unit, and means for separating a part of the pulp below the surface in the agitating compartment and causing it to 25 overflow at the top into the agitating compartment of the adjacent unit independent of the overflow into said separating compartment.

7. In flotation apparatus, the combination 30 of a plurality of units each comprising an agitating compartment and a separating compartment, the partition between the two agitating compartments of adjacent units and the partition between the agitating and separating compartments of each unit being of 35 the same height, and a baffle spaced from the partition separating the two agitating compartments of adjacent units and extending both above and below the level of the top 40 of the adjacent partitions, the two compartments of any unit being in communication with each other at the bottom and means for circulating the pulp from the separating compartment into the agitating compartment of each unit.

8. In flotation apparatus, the combination 45 of a plurality of units, each comprising an agitating compartment and a separating compartment in communication at the bottom, means located in the agitating compartment of each unit for circulating the pulp from the separating compartment into the agitating compartment, means for causing the pulp to overflow from the top of an agitating compartment into the separating compartment of the same unit, and means for causing the pulp to overflow from the agitating compartment of one unit into the agitating compartment of the adjacent unit.

60 9. In flotation apparatus, the combination 50 of a plurality of units, each comprising an agitating compartment and a separating compartment in communication at the bottom, means located in the agitating compartment of each unit for circulating the pulp

from the separating compartment into the agitating compartment, means for causing the pulp to overflow from the top of an agitating compartment into the separating compartment of the same unit, and means 70 for causing the pulp to overflow from the agitating compartment of one unit into the agitating compartment of the adjacent unit, said last named means including a baffle device spaced from the partition separating 75 the agitating compartments of adjacent units and extending both above and below the upper edge of said partition, said device also separating the passage between the baffle and the said partition from the separating compartment of the unit. 80

10. In flotation apparatus, a plurality of units each comprising an agitating compartment and a separating compartment, one of said compartments being arranged at 85 the side of the other, the agitating compartment of one unit having an overflow into the separating compartment of its own unit, and an overflow into the contiguous agitating compartment of the adjacent unit. 90

11. In flotation apparatus, the combination 95 of a plurality of units each comprising an agitating compartment and a separating compartment, one of said compartments being arranged at the side of the other, the agitating compartment of one unit having a free overflow from the top into the separating compartment of its own unit, and a restricted overflow into the contiguous agitating compartment of the adjacent unit. 100

12. In flotation apparatus, the combination 105 of a plurality of units each comprising an agitating compartment and a separating compartment, one of said compartments being arranged at the side of the other, means for causing a free overflow from the top of the agitating compartment of one unit into the separating compartment of its own unit, and means for causing a restricted overflow from the agitating compartment of one unit into the contiguous agitating compartment of the adjacent unit. 110

13. In flotation apparatus the combination 115 of a plurality of units each comprising an agitating compartment and a separating compartment, one of said compartments being arranged at the side of the other, means for causing the pulp to overflow from the agitating compartment of one unit into the separating compartment of the same unit, 120 and means for separating a part of the pulp below the surface in the agitating compartment and causing it to overflow at the top into the agitating compartment of the adjacent unit. 125

14. In flotation apparatus the combination 130 of a plurality of units each comprising an agitating compartment and a separating compartment, means for causing the pulp to overflow from the agitating compartment

- of one unit into the separating compartment of the same unit, and means for separating a part of the pulp below the surface in the agitating compartment and causing it to overflow at the top into the agitating compartment of the adjacent unit, said separating means comprising a baffle extending above and below the point of the last-named overflow.
10. 15. In flotation apparatus a plurality of units, each unit comprising an agitating compartment and a separating compartment, one of said compartments being arranged at the side of the other, means for causing 15 a free overflow from the top of the agitating compartment of one unit into the separating compartment of the same unit, and means for causing a restricted overflow from the agitating compartment of one unit into 20 the adjacent unit.
16. In flotation apparatus a plurality of units, each unit comprising an agitating compartment and a separating compartment, said compartments being at the side of one 25 another, the agitating compartment of one unit having an overflow into the separating compartment of the same unit and an overflow into the adjacent unit independent of the overflow into said separating compartment.
30. 17. In flotation apparatus a plurality of units, each unit comprising an agitating compartment and a separating compartment, one of said compartments being arranged at the side of the other, means for determining a liquid level in the compartments, the agitating compartment having a free unobstructed overflow into the separating compartment below the liquid level, and an overflow into the adjacent unit independent 40 of the overflow into said separating compartment.
18. Flotation apparatus comprising an agitating compartment and a separating compartment, means for maintaining the 45 same pulp level in both compartments, a partition between the compartments terminating below the pulp level, the agitating compartment having an overflow into the separating compartment below the pulp 50 level, the separating compartment having a froth overflow, the space above said pulp level being free of obstruction in order to permit free movement of froth toward said froth overflow, a connection between the 55 lower portion of the separating compartment and the lower portion of the agitating compartment, and a discharge overflow from said agitating compartment independent of the overflow into said separating compartment.

In testimony whereof I affix my signature.

JOSEPH P. RUTH, JR.
